UNITED STATES PATENT OFFICE.

HARRY WILSIE, OF BROOKLYN, NEW YORK, ASSIGNOR OF ONE-HALF TO M. J. FORD,
OF NEW YORK, N. Y.

MACHINE FOR LOCK-JOINING TUBES.

1,190,351.

Specification of Letters Patent. Patented July 11, 1916.

Application filed August 20, 1915. Serial No. 46,413.

To all whom it may concern:

Be it known that I, HARRY WILSIE, a citizen of the United States, residing at Brooklyn, in the county of Kings and State of New York, have invented certain new and useful Improvements in Machines for Lock-Joining Tubes, of which the following is a specification, reference being had thereto in the accompanying drawing.

This invention relates to improvements in machines for forming sheet metal tubes, and more specifically to apparatus for simultaneously shaping to the tube form a sheet metal blank and interlocking the edges of the tube to provide a lock joint of water, air and oil-tight character and permitting the tube to be bent within reasonable limits without injury to the lock joint.

The invention primarily contemplates the provision of a machine of the type above designated, adapted to perform its expected functions by a drawing action of the sheet metal therethrough.

Improved details in construction and arrangement of parts will be apparent from the specific description hereinafter contained, when read in connection with the accompanying drawings forming part hereof and wherein a preferred embodiment of the invention is illustrated for the sake of imparting a full and clear understanding of the latter.

In the drawings: Figure 1 is a side elevation of the machine; Fig. 2 is a transverse sectional view through the initial joint bending rolls; Figs. 3, 4, 5 and 6 are transverse sectional views showing the various edge interlocking means; and Figs. 7 and 8 are end views, respectively, showing the tube-blank in U-form, and with its edges overlapped.

Referring more specifically to the drawings wherein like reference characters designate corresponding parts in the several views, A represents a supporting table or bench adjacent to one end of which, and arranged in alinement, are three supports, B, C and D, arranged in the order designated, and firmly anchored to the floor or its equivalent, as by bolts, b, c and d.

On the support B, I rotatably mount, through the medium of a spool E, the roll of sheet metal F of any size desired, having its feed end carried outwardly, as at G, through a suitable guide H, formed at the

upper end of the support C, said sheet being delivered from the guide between an initial pair of forming rolls I, I', the former (upper) being axially convexed on its periphery, and the latter (lower) being axially concaved on its periphery, to the end that the rolls in the passage of the sheet therethrough, will bend the same into a trough-like formation, having its base rounded on the arc of a circle, in keeping with the predetermined configuration of the ultimate tube.

Mounted for a freedom of movement, or self-adjustment, so to speak, upon the face of the table or work bench A is a two-part carrier, J, J', of rectangular formation to rest properly on the table or bench, the same being limited in its longitudinal movement by stops j, on the table. These stops j, one located intermediate of the carrier members J, J', and the other at the discharging end of the device, are secured to the work-bench A, the former stop being merely a block, whereas the latter is an upright, apertured as shown for the reception of the end of the die support K, when the machine is operating and the device is pulled to the right as illustrated in Fig. 1.

Extending through both carrier members J, J' is a die support K, the same being of a slotted cylindrical nature, having its inner end hung upon a bracket L, bolted at l, to the top of the carrier member J, and having a centering screw l' engaging the end of the die support. The carrier member J, surrounding the die support K, is formed with a longitudinally disposed inwardly tapering opening M, capable of receiving the trough or U-shaped sheet of metal from the rolls I, I', and by the co-operation of the members J, K, bending the U-formation into a cylindrical formation with the edges of the sheet overlapping, as will be obvious.

The carrier members J, J' are bridged, as at N, by a bracket which supports intermediate of said members, a suitable guide roller O, beneath which the tubular sheet is passed and by which it is guided to the joint or seam forming dies, now to be defined, the roller O being of peripheral formation to overlie the overlapped edges of the tube and maintain the same in proper position on the member K for presentation of the overlapped edges to the die members.

That portion of the support K which

passes through the carrier member *J'* is formed in its upper surface with a way or groove *P*, the inner end of which, being that end first encountered by the tube, as it is drawn through the machine, having a die *Q* in the face of which is a slot having an approximately semi-circular wall for initially bending inwardly into correspondingly curved formation the overlapped edges of the tubular sheet, a ribbed rotatable male die *R*, coöperating with the female die just referred to. From this point in the operation of the machine the tube is drawn to the succeeding die *S*, fixed in the groove of the die supporting member, the recess or groove of this particular die having parallel side walls and rounded bottom adapted to press together, or close to some extent, the U-shaped joint formed by the dies *Q* and *R*. The coöperating die member in this instance is represented at *S'*. The succeeding die, also fixed in the supporting member *K*, is represented at *T*, and its coöperating member at *T'*, the die *T*, in this case, being formed with one straight side wall and an inclined base wall adapted to turn to one side of the longitudinal center of the tube and further close the interlocking joint. From the die *T* the tube is drawn to the next die *U*, which also has one straight wall and an inclined base wall so related, however, that the groove is relatively shallow with reference to the groove of the die *T*, this die coöperating with its companion member *U* to press inwardly the interlocking joint, as clearly illustrated.

The final die is indicated at *V*, the same employing a groove having straight side and bottom walls and being of quite shallow depth to coöperate with its complementary die member *V'* to finally press the lock joint against the body of the tube. The lock joint thus formed is well adapted to prevent leakage of any kind therefrom, and to perform its other expected functions. The various die members *S'*, *T'*, *U'* and *V'* are held in position on the die support *K* in any suitable manner and the whole of the lock joint forming means is freely mounted on the bench, as heretofore indicated, to permit the same to adjust itself to conditions by slight lateral or longitudinal movements to avoid friction, etc. The initial die roller *R* is held in proper relation to the coöperating die *Q* by means of a slab or cover piece *W*, bolted as at *w*, to the body of the member *J'*, springs *w'* being interposed therebetween to hold the roller *R* elevated to present the proper space between the same and the die *Q* to accommodate the thickness of the sheet metal at the overlapped portion thereof immediately adjacent to said roller.

When starting the operation of the machine, the sheet metal is provided with a narrow tongue which is passed entirely

through the lock joint forming mechanism and gripped, as at the point indicated by *X*, by a bench dog or clamp coupled with suitable mechanism, not shown, for drawing the sheet through the tube forming and joining or seaming devices.

From the foregoing it will be appreciated that in a simple effective way I have provided a machine capable of expeditiously and at the same time at minimum cost producing a lock jointed sheet metal tube, a machine of such mechanical construction as will need but little repair, and an arrangement of die members in a manner enabling their removal from the supports or parts to which they are connected for the purpose of repair, substitution or renewal, as occasion may demand.

While I have herein disclosed one specific embodiment of the invention, it will be apparent to persons skilled in the art that the invention is capable of embodiment in other forms and devices without departing from the spirit thereof and as may be in keeping with the hereto appended claims.

Having thus described the invention, what is claimed is:

1. In a machine for lock joining tubes, the combination with means for bending a sheet into tubular formation with overlapping edges, of means for bending said overlapped edges into U-formation to constitute a joint, outside die members, a grooved die carrier adapted to occupy a position within the tube, and axially aligned successively acting die members occupying relatively fixed positions in said groove, some of which have a straight side wall and inclined base wall to close the joint and to upset the same from a vertical to an approximately horizontal position, substantially as described.

2. In a machine for lock joining tubes, the combination with means for bending a sheet into tubular formation with overlapping edges, of means for bending said overlapped edges into U-formation to constitute a joint, outside die members, a grooved die carrier adapted to occupy a position within the tube, and axially aligned successively acting die members occupying relatively fixed positions in said groove, some of which have a straight side wall and inclined base wall to close the joint and to upset the same from a vertical to an approximately horizontal position, said dies with the inclined base walls decreasing in depth and the final die being straight and adapted to effectually close the joint and cause the same to lie approximately in the plane of the wall of the tube, substantially as described.

3. In a machine of the character described, a die support, a depressing member at one end of the same for closing the tube with overlapped edges, a guide roller adapted to engage said overlapped edges to maintain

- them in proper position for presentation to die members, and a preliminary die for initially depressing said overlapped edges in combination with a succession of dies 5 mounted in the die support adapted to operate interiorly of the tube on the overlapped edges thereof, and complementary die members arranged to operate exteriorly of the tube, substantially as described.
- 19 4. In a machine of the character described, means for forming a sheet into trough formation, means for closing the trough formation into a tube with overlapped edges, means for depressing the overlapped edges into a curved interlocked relation, means for closing the depressed portion into a more definite rib with straight sides, means for deflecting the rib laterally, means for further laying the rib toward the wall of the 50 tube, and means for finally compressing the walls of the rib together in flat condition, substantially in the plane of the wall of the tube, substantially as described.
- 15 5. In a machine of the character described, means for forming a sheet into trough formation, means for closing the trough formation into a tube with overlapped edges, means for depressing the overlapped edges into a curved interlocked relation, means for closing the depressed portion into a more definite rib with straight sides, means for deflecting the rib laterally, means for further laying the rib toward the wall of the 55 tube, and means for finally compressing the walls of the rib together in flat condition, substantially in the plane of the wall of the tube, substantially as described.
- 20 6. In a machine of the character described, means for forming a sheet into trough formation, means for closing the trough formation into a tube with overlapped edges, means for depressing the overlapped edges into a curved interlocked relation, means for closing the depressed portion into a more definite rib with straight sides, means for deflecting the rib laterally, means for further laying the rib toward the wall of the 60 tube, and means for finally compressing the walls of the rib together in flat condition, substantially in the plane of the wall of the tube, substantially as described.
- 25 7. In a machine of the character described, means for forming a sheet into tube formation with overlapped edge portions, means for depressing the overlapped edge portions into a relatively open interlocked relation, means for closing the depressed portion of the tube into a more definite rib with straight sides, means for deflecting 65 and laying the rib toward the wall of the tube, and means for pressing the rib in a flat condition against the wall of the tube, substantially as described.
- 30 In testimony whereof I hereunto affix my 70 signature in the presence of two witnesses.
